G. Kennedy,
ATTORNEY

UNITED STATES PATENT OFFICE

JAMES A. WILEY, OF CEDAR FALLS, IOWA

SELECTIVE SCORE INDICATOR FOR TESTS

Application filed January 30, 1931. Serial No. 512,380.

My invention relates to improvements in selective score indicators for tests, and the object of my improvement is to supply for collegiate or other testers, an apparatus for convenient use by a person under test in marking therein for subsequent inspection indications for answers to questions on a questionnaire, whereby such inspection will disclose to the tester at a glance either the correct or incorrect markings for computation in making up a score in such an examination.

Another object of my improvements is to arrange different elements of the apparatus in a definite order, and with certain apertures for use in markings of varying sizes or diameters, whereby the person under examination in making such markings cannot disclose to others by such markings the actual condition of his test by casual inspection of the combined elements before their separation for inspection by the tester of the answer receiving sheets therein.

These objects I have accomplished by the means which are hereinafter described and claimed, and which are illustrated in the accompanying drawings, in which Figs. 1 and 2 are respectively front elevations of permanent front and rear covers of the apparatus, Fig. 1 showing the apertured front cover, the rear cover of Fig. 2 being imperforate. Fig. 3 is a view in perspective of the double flap sheet filler for use between and in registration with said covers, the front flap having certain apertures larger than and to be positioned back of certain of the smaller apertures in the front cover, while the rear flap is imperforate.

As above stated, the uses of my improved testing apparatus are these, first, to prevent copying of a test answer marking therein by another person than the one being examined, and second, the recording on the inner sheets of the apparatus of indications made by the person being examined, and whereby the

correctness of the answers may be quickly determined by inspection of the removed sheets by the tester.

In my said apparatus, the numeral 1 denotes the front cover thereof, preferably made of wood or metal, as is also the rear cover 2, the latter being imperforate, the former having numerous characteristically arranged like small diameter apertures or holes 5 in both horizontal and vertical rows 55 of like numbers.

As shown in said Fig. 3, the numeral 3 denotes a sheet having a single fold providing like registering parts or flaps of which the rear flap 4 is unmarked and imperforate, 60 while the front flap has punched or otherwise formed therein a limited number of holes 8 which are of larger size or diameter than the holes 5 in the top cover 1, and when the doubled sheet 3 is inserted between the 65 covers 1 and 2 in registration therewith, are behind certain of the smaller holes 5 in the top cover, concentric therewith, and being larger, are effectively concealed as such holes behind the front cover, as the inner edges of 70 the larger holes 8 are covered by the front cover, and because of the relative thinness of the flap 3, the locations of these larger holes 8 cannot be described by a person looking at the assembly.

The apparatus is employed by a tester in taking answer markings through the cover holes 5, as by a pencil or other means, made by the pupil or other person under test, said answers being responsive to certain suggested 80 answers only on a questionnaire, of which an exemplification is given below.

Questionary

1. The capital city of Iowa is: 85
  - (a) Ottumwa.
  - (b) Iowa City.
  - (c) Davenport.
  - (d) Des Moines.
  - (e) Waterloo. 90

2. The most reliable indication that a particular human trait is native, is:
- Universality.
  - Presence in primates.
  - Value to the species.
  - Present at birth.
  - Appearance without a chance to learn.
3. All parts of the eye are accessory except:
- The pupil.
  - The lens.
  - The iris.
  - The cornea.
  - The retina.

Referring to said Fig. 1, the numeral 6 denotes in a vertical row of ordinals the three questions or propositions 1, 2 and 3 of said questionnaire, whose suggested answers (a) to (e) inclusive also shown on the questionnaire, are represented by the same characters (a) to (e) inclusive shown in a horizontal row at the top of the cover 1 over the vertical rows of holes 5 of the cover. It will be understood that any suitable securing or clamping means may be used to keep the covers 1 and 2 with the inserted sheets or flaps 3 and 4 together against displacements or tampering, but this invention inheres at any rate in the pile of said elements whether fastened together or not.

30 The student under test, using a pencil or the like, will after considering each proposition of the questionnaire serially, and if so considering question 1, mark through one of the holes 5 of the cover 1 in the upper horizontal row a cross 9' or any other marking, such as a circle within the circle of the selected hole, at the hole under the letter *e*, as shown in Fig. 1. He proceeds in the same way to set down markings in one hole 40 each of the horizontal rows opposite the ordinals 2 and 3, for a selected answer taken from the suggested answers of the respective questions. For instance, in Fig. 1, he may have marked the given sign through the hole at *c*, in the first, at *d* in the second, and at *e* in the top three rows which correspond to said three propositions on the questionnaire. The markings will show through all said holes, but the marker, and any onlooker, cannot see or determine whether his markings have passed through the larger diameter holes 8 of the top flap 3 of paper inserted between the covers, for the edges of said larger holes are concealed beneath the top cover 1, as indicated in dotted lines in Fig. 1. The three larger holes 8 of the sheet or flap 3 are located and indicate the correct answers to the questionnaire, consequently in the example 50 shown, the correctly placed markings 9 will be penciled on the blank imperforate rear sheet or flap 4, making a record there for the tester's use, of the number of questions or propositions correctly answered. On the other hand, the marking 9' is made on the

upper sheet or flap 3, indicating an incorrect answer for scoring by the tester.

It will be seen, that the tester is thus supplied on the upper sheet 3 with markings indicating incorrect answers, and on the lower sheet 4 with markings indicating the correct answers, and in scoring may employ either in determining the grade of the student. Instead of using a folded sheet as shown to receive on its upper and lower parts the markings made as described, two separate sheets of the same shape and size as also material, may be superposed and placed between the covers 1 and 2 for the recording.

It will also be understood, that the drawings are exemplifications of a simple character, and for single test purposes. Without departing from this invention, the record sheets 3 and 4 may be rotated for the use of its lower end in an upper position for a second test, or in place of an imperforate rear cover 2, the rear cover may have like rows of holes 5, but relatively staggered or alternated so that markings through said rear holes will impress indications on the rear faces of other sheets 3 and 4 placed in the apparatus also for such other tests, while all in one appliance. These changes are therefore duplications, and within the scope of my claims.

Having described my invention, what I claim as new, and desire to secure by Letters Patent, is:

1. Apparatus of the character described, comprising in combination, front and rear superposed registering covers, the front cover having numerous like holes of small diameter arranged in both horizontal and vertical rows to correspond respectively to questions of a questionnaire and to suggested answers thereof on the questionnaire, and sheets between said covers, the forward sheet having holes of greater diameter than those of the front cover, under and concentric with the cover holes and concealed by the cover, the rear sheet being imperforate, and the rear cover being imperforate.

2. In apparatus of the character described, a cover having holes of relatively small diameter, a pair of sheets below said cover, the forward sheet having fewer holes of greater diameter than the cover holes, positioned below the cover holes concentric therearound and concealed by the cover, and the rear sheet being imperforate.

3. In apparatus of the character described, a cover having regularly arranged rows of holes of relatively small diameter and related in arrangement to the arrangement of certain questions and suggested answers on a questionnaire, and a folded record sheet beneath said cover consisting of the forward part having larger holes and superposed parts to receive markings on the forward part only through the cover holes not aligned with the

larger holes on the forward part, the rear part of the sheet being imperforate and to receive markings only through the aligned smaller and larger holes respectively of the cover and
5 said forward sheet part.

In testimony whereof I affix my signature.

JAMES A. WILEY.
